Providence, R.I., assignors to Dart Industries Inc., Los
Angeles, Calif.

Filed July 22, 1971, Ser. No. 165,435

Term of patent 14 years

Int. Cl. D7—01

U.S. Cl. D7—21

FIG. 1

FIG. 2

FIG. 3

FIG. 4

FIG. 1 is a top perspective view of a serving bowl or the like showing our new design;

FIG. 2 is a bottom view thereof;

FIG. 3 is a side elevational view thereof; and

FIG. 4 is a front elevational view thereof.

Among others the ornamental design of the serving bowl or the like is particularly characterized by a peripherally extending flange positioned proximate the bowl rim, which flange is concavely disposed upwardly and smoothly blends into two oppositely disposed handle members of an upwardly convex disposition.

We claim:

The ornamental design for a serving bowl or the like, substantially as shown and described.
